UNITED STATES PATENT OFFICE

2,429,669

PRESS

Alfred R. Crawford, Bridgeton, N. J., assignor to
 Ferracute Machine Company, Bridgeton, N. J.,
 a corporation of New Jersey

Application August 22, 1945, Serial No. 611,995

6 Claims. (Cl. 164—103)

1

This invention relates to an elevating and adjusting device for presses of the class embodying a frame which carries the operating means of the press, and is pivotally and adjustably mounted on a base.

It has been found that presses which may be elevated and adjusted present great hazards for the workmen engaged in the elevation thereof. According to the present invention, the hazards to the workmen, particularly those behind the press, are eliminated.

The construction of a press which eliminates hazards to the workmen engaged in the elevation thereof has to include locking means for holding the frame in the position desired after the adjusting operation.

Accordingly, it is an object of this invention to provide a press with means for elevation and adjustment of the same so as to eliminate the hazard to the workmen engaged in such elevation.

It is another object of the invention to relieve the locking means for holding the frame in position from the stress exerted by the weight of the adjustable part of the press during the adjusting operation.

It is a further object of the invention to simplify the construction and the handling of such an elevating and adjusting device having the necessary strength and stability.

Other objects and advantages of the invention will be apparent from the following description and the accompanying drawings in which:

Fig. 1 is a diagrammatic side elevation of the press provided with an elevating and adjusting device according to the invention, said device being shown with the adjustable part of the press in upright position.

Fig. 2 is a front view of the press shown in Fig. 1.

Fig. 3 is a side view of the lower portion of the press shown in Fig. 1 with the adjustable part in inclined position.

Fig. 4 is a section on a larger scale through the elevating and adjusting device, taken on the line 4—4 of Fig. 2.

Numeral 1 indicates the base of the press. Numeral 2 indicates the frame carrying the bed 28 and the usual tool holder and driving elements of the press (not shown in the drawing). Said frame is pivotally secured to the base 1 by bolts 3, 3, and is held in any one of the desired positions by bolts 4, 4 passing through holes 5, 5 in said frame and through one of the pairs of holes 6, 6, 7, 7 and 8, 8 in the base 1.

The elevating and adjusting device comprises a 55 shown in Fig. 3 to the position shown in Figs. 1

2

piston rod 9, one end of said piston rod being pivotally secured to bracket 10 attached to the lower end of the frame 2. The other end of the piston rod 9 is attached to a piston 11 movable in a cylinder 12, which is pivotally secured at 13 to the base 1. The outward movement of the piston 11 is effected by a fluid, preferably oil, delivered into the cylinder 12 by a pump 14 fixed to said cylinder 12.

10 The pump comprises a piston 15 movable in a bore 16 in the cylinder head 17. The front end of the bore 16 is connected by a conduit 18 provided with a suction valve 19 (replaceable ball check type) to a fluid container which is preferably formed by a jacket 20 surrounding the cylinder 12. A branch pipe 21 connects the section of the conduit 18 between the bore 16 and the valve 19 with the cylinder 12. A pressure valve 22 (replaceable ball check type) controls the flow of the 15 fluid through said pipe 21. Another connection between the container 20 and the cylinder 12 is formed by another bore 23 in the cylinder head 17, said connection being controlled by a hand operated needle valve 24 screwed in a bore 26 of 20 the cylinder head 17.

25 The piston 15 is actuated by a lever 25 linked to said piston and to the cylinder head 17. The outer end of the lever 25 is adapted to receive one end of a handle 27, the other end of said 30 handle being shaped as to fit into or on a correspondingly shaped part of the head of the needle valve 24.

When the press is in upright position as shown in Figs. 1 and 2 the needle, or bleeding valve, is 35 closed, and therefore the connection between the container 20 and the cylinder 12 is interrupted. The press is locked in this position by the bolts 4, 4. In order to bring the press to the inclined 40 position shown in Fig. 3 the bolts 4, 4 are removed and the needle valve is slightly opened by means of the handle 27. As the weight of the turntable part of the press is now entirely transmitted by the piston rod 9 to the piston 11 the fluid in the cylinder 12 is slowly pressed back 45 through the bore 23 into the container 20. As the opening of the valve 24 is very small a braking action is obtained, so that the press is very slowly turned, and may be stopped at any moment by closing the valve 24. After reaching the 50 desired position and closing the valve 24 the bolts 4, 4 are inserted into the holes, 5, 5, of the frame 2 and the holes, 7, 7, of the base 1, locking thereby the press in the desired inclined position.

In order to elevate the press from the position

and 2, the handle 27 is inserted into the socket at the end of the lever 25 and a slight pumping action is performed, just enough to relieve the locking bolts 4, 4 from the weight of the turnable part of the press. After removing the bolts 4, 4 pumping is continued until the upright position is reached, whereupon the press is again locked in this position by inserting the locking bolts 4, 4.

While I have particularly illustrated and described one embodiment of my invention, it should be understood that my invention is not limited thereto or thereby but is defined in the appended claims.

I claim:

1. An elevating and adjusting device for a press, having a frame pivotally mounted on a base, said device comprising a piston rod linked to said frame and operated by a piston working in a cylinder linked to said base, and locking means holding the pivotable part of the press in the desired position.

2. In a fluid operated elevating and adjusting device as defined in claim 1, a pump delivering the driving fluid to the pivotable cylinder, said pump being mounted on said cylinder.

3. In a fluid operated elevating and adjusting device as defined in claim 1, a tank and a pump delivering the fluid from said tank to the cylinder, both the tank and the pump being mounted on said cylinder.

4. In a fluid operated elevating and adjusting

device as defined in claim 1, a tank and a pump delivering the fluid from said tank to the pivotable cylinder, and a bleeding valve controlling a connection between said tank and said cylinder.

5. In a fluid operated elevating and adjusting device as defined in claim 1, a tank and a pump delivering the fluid from said tank to the pivotable cylinder, a bleeding valve controlling a connection between said tank and said cylinder, both the tank, the pump and the bleeding valve being mounted on said cylinder.

6. In a fluid operated elevating and adjusting device as defined in claim 1, a tank and a pump delivering the fluid from said tank to the pivotable cylinder, a bleeding valve controlling a connection between said tank and said cylinder, a leverage secured to the aforesaid cylinder and adapted to operate the aforesaid pump, the last member of said leverage being adapted to receive a removable handle which is also adapted to operate the aforesaid bleeding valve.

ALFRED R. CRAWFORD.
